UNITED STATES PATENT OFFICE.

ARTHUR CHARLES WOOD, OF MANSFIELD, OHIO.

MOTOR LAMP.

Application filed September 2, 1921. Serial No. 497,861.

To all whom it may concern:

Be it known that I, ARTHUR CHARLES WOOD, a subject of Great Britain, residing at Mansfield, in the county of Richland and State of Ohio, have invented certain new and useful Improvements in Motor Lamps, of which the following is a specification.

This invention relates to means for controlling the light rays of reflector lamps.

10 It is well known to those skilled in the art of constructing lamps, head lights or the like, especially for use on motor cars, that an intense glare is projected into the eyes of an oncoming driver blinding his vision, unless means are provided within the control of the driver of the oncoming car to dim the lights or to change the direction of the projection of the light rays emitting therefrom. The conventional type of 15 tilting reflectors which are designed to prevent blinding effect on the vision of the driver of the oncoming car, performs this function with more or less efficiency and disadvantages.

20 It is well known also to those skilled in the art that in tilting the reflector after it is moved to prevent the glare into the eyes of an oncoming driver that the light rays gradually spread out laterally or expand to a critical point before dimming dissipating or producing what is termed a "black spot" 25 on the road ahead of the car making it difficult to see objects on the road bed at a certain required distance from the car.

30 The primary object of the present invention therefore is to provide means and mechanism applicable to the conventional or similar type of reflector lamp to tilt same to a pre-determined point independent of 35 the light source and at such pre-determined point move the light source and further tilt the reflector simultaneously therewith, thereby preserving the focus of the light with respect to the reflector and maintaining 40 the intensity of the glare so as to prevent its dissipation or dimming and the resultant "dark spot" on the road ahead of the car which is incident to the use or operation of a reflector that is tilted independent 45 of the focus of the light source.

50 In other words it is the object of the present invention to tilt the reflector independent of the light source to obtain its greatest lateral spread or expansion without dimming or dissipating the glare of the light projected ahead of the car and when

said point or relative pre-determined tilted position is reached, further tilting the reflector and moving the reflector and the light source simultaneously thereby maintaining the same relative position of the light source and reflector, retaining the same intensity of the projecting rays of light by maintaining the same focus of the light source with respect to the reflector, irrespective of the further tilted position of the reflector contracting and concentrating the rays of light on the road ahead of the car.

55 A further object is to provide adjustable means for focusing the light source with respect to the axial opening or central portion of the reflector.

60 Another object is to provide means of imparting unison or simultaneous movement to the light source and reflector at any point of the tilting movement or position of the reflector.

65 A further object is to provide means for tilting the reflector from normal position to no-glare position, and finally the object 70 of the present invention is to provide means that will comply with the tests of the dimming and anti-glare statutes or laws of the State of Ohio and other States which require among other things full illumination and projection of the light rays ahead of the motor car a certain number of feet when the reflector is in normal position or in full glare, full illumination for a certain 75 number of feet ahead of the car when the reflector is tilted to no-glare position and means to control the rays of light from the reflector to project below the vision or eyes 80 of a driver of an oncoming car.

85 These and other objects are attained by 85 the mechanism illustrated in the accompanying drawing in which:—

90 Fig. 1, is a longitudinal view partly in section of a lamp or head light, in normal position showing the invention applied thereto.

95 Fig. 2, is an enlarged longitudinal section of a part of the lamp showing the means of adjusting the bell crank contact, that moves the light source in unison with the reflector when tilting movement is imparted thereto.

100 Fig. 3, is a rear elevation of Fig. 1, showing operating crank shaft and means of supporting the lamp socket holder.

110 The drawing shows the preferred form and the application thereof to a conven-

tional type of motor car head light, lamp or the like.

Referring to the drawings reference numeral 1 represents the casing of the lamp, 5 2 the glass cover plate and 3 the annular holding means or beaded ring. The reflector 4 is hinged at the top as indicated by the hinge 5 and is adapted to be tilted rearwardly for the purpose described when 10 desired by the operator.

An axial opening 6 preferably elongated is formed in the center of reflector. The reflector is tilted rearwardly by any well known manner. The means shown in the 15 drawing comprises the following instrumentalities and in applying same an ear 7 is fastened to the reflector in any well known manner. A link 8 is pivoted thereto supporting a link lever 9 which is mounted 20 upon and fastened rigidly to a rotatable shaft 10. The shaft is journaled on a bearing secured to the auxiliary casing which extends into a pocket 12 formed by an auxiliary casing 11.

25 The aforementioned mechanism operates as follows: The operator imparts movement to the lever 14 or the like tilting the reflector 4 when it is desired to attain the objects of the invention. A compressed coil 30 spring 15 is attached to the casing 1 and the reflector 4 exerting its pressure or tension to retain and return the reflector to its rearward or tilted no-glare position or safety position.

35 A bracket 16 is supported on the casing near the axial opening 6 of the reflector preferably by the bolts 17 and 18 and the threaded ends thereof engage threaded apertures formed in the supporting bracket 40 and pass through apertures in the casing leaving the heads of the bolts extending beyond the exterior of the casing. Expansible springs 19 and 20 are interposed between the casing and bracket exerting a pressure 45 or tension against the casing and bracket, thereby maintaining the supporting bracket in proper position with respect to the axial opening 6 of the reflector and at the same time permitting adjustment of the 50 screws 17 and 18 for focusing purposes.

The supporting bracket 16 is preferably provided with a socket member 21 which preferably depends downwardly in angular relation to the opening 6 of the reflector 4 and is provided with a longitudinal slot 22. A lamp socket holder 23 having an angularly related socket member 24 is provided. The angularly related socket member 24 is telescopically fitted to the socket member 60 21 and is adapted to slide within said socket member. The sliding movement of the member 24 is guided and controlled by a pin 25 which projects into a slot 22 formed in the socket member 21 and it also limits its longitudinal movement in either direc-

tion. The light source 26 which in the drawing is represented by an incandescent electric globe is connected to the socket holder 23 through the medium of a bayonet joint or the like 27. The socket holder 23 is provided with a downwardly projecting contact member 28 which projects from the socket holder in angular relation thereto and in substantial alignment with the center of the angularly related parts 24 and 21. 75

A bracket 29 is located directly underneath the contact member 28 and is attached to the reflector 4. A bell crank lever 30 is pivotally journaled to the bracket 29 by means of a pin 31, leaving one end projecting upwardly and in close proximity to the contact member 28 and the other end projects downwardly and it is threadably connected to an adjustable screw 32 and is held in any adjusted position by the lock nut 33. 85 The bell crank lever can be adjusted as shown in Fig. 2, to and from the dotted line position indicated at 34 in Fig. 2.

The above describes the preferred mechanism used to apply the invention to a conventional type of lamp or headlight for motor cars. The operation is as follows: The incandescent lamp 26 is secured to the socket 23 and properly focused with relation to the reflector by adjusting the screws 90 17 and 18 which support the bracket 16 and the socket members 21 and 24. When the incandescent light is properly focused with respect to the reflector and the reflector is in normal position as shown in Fig. 1, the 100 rays of light are directed on the road bed directly ahead of the motor car illuminating the road bed the required or pre-determined distance ahead of the car which is governed or regulated by the focus of the 105 light in its relation to the reflector and the candle power of the light source or incandescent bulb. When the reflector is in normal position the rays of light or glare will project into the eyes of the driver of an oncoming car and blind his vision. In the 110 normal position the reflector projects the light rays ahead of the automobile giving the driver of a car equipped with the present invention full, complete, intense illumination and glare ahead of his car, but the light rays ordinarily glare into the eyes of the 115 driver of an oncoming car. To provide for the safety of an oncoming or approaching car and driver and to comply with various 120 State dimming or no glare laws, the intensity of the glare must be dimmed or the rays of light directed away from the eyes or vision of the driver of the oncoming car. To accomplish these objects the operator of 125 the present device, in the first instance manipulates the lever 14 which actuates the connecting mechanism to tilt the reflector 4, thereby tilting the reflector rearward, independent of the incandescent bulb 130

or light source 26 which remains stationary projecting rays of light forward and expanding or spreading the light rays in a lateral direction on each side of the motor 5 car lighting on the road bed and adjacent ditches with the same intense glare and illumination as the light was projected ahead before changing the direction of the projection of the rays of light downwardly 10 on the road bed and away from the eyes or vision of the driver of an oncoming car.

The tilting movement described of the reflector independent of the light source is continued by the operator until a pre-determined 15 tilted position of the reflector is reached which position is preferably determined to be the position at which the spread or expansion of light commence to 20 dim, diminish or is dissipated in intensity or glare producing what is termed a "black spot" with respect to the illumination of the road bed ahead of the car making it difficult to see objects on the road bed. Just prior to the time that tilting reflector reaches the 25 full spread or expansion of its rays of light without dimming, or dissipating the light or producing the black spot the contact member 28 is brought and forced to contact with the bell crank lever 30 moving the 30 light source and reflector together in unison or simultaneously therewith, thereby preventing the dimming or dissipating of the rays of light or production of the "black spot" on the road bed.

Moving the light source simultaneously or 35 in unison with the reflector contracts the rays of light and intensifies its glare as the reflector is moved or tilted further rearwardly from the first tilted position. In moving 40 the light source and reflector in unison or simultaneously from a pre-determined point, the position of the light source in relation to the reflector is then maintained, thereby preventing the dissipation dimming of the 45 light from the critical point of the expansion or spread due to the first tilted position of the reflector.

It will be observed that the tilting reflector 4 can be moved to certain or pre-determined tilted position, independent of a 50 light source and at such pre-determined position the bell crank is adjusted to contact with the contact piece 28, moving the light source simultaneously or in unison with the reflector.

The adjustment of the contact piece to operate the light source and reflector simultaneously is accomplished by the adjustment 55 of the screw 32. The tilting mechanism of the reflector is limited in its rearward movement after actuation by the screw 35.

Reference numeral 36 represents a conventional socket to conduct an electric current to the incandescent bulb or light source. 60 65 It is not intended in the within specification

to confine the present invention to the specific means or mechanism shown in the drawings as immaterial alterations or modifications may be made to accomplish the objects herein set out without departing from the 70 spirit of the invention.

I claim.

1. A method of controlling the light rays of a reflector lamp, consisting in changing the focal relation of the light source and reflector while changing the direction of the light rays, then fixing the focal relation of the light source and reflector to prevent further change in such focal relation during further change in the direction of the light 75 rays.

2. A method of controlling the light rays of a reflector lamp, consisting in changing the direction of such light rays with respect to the horizontal, changing the focal relation of the reflector and light source during a portion of such direction change, and fixing the focal relation of the reflector and light source during the remainder of such direction change, whereby in the start of 85 such direction change the light rays are diffused and such diffusion is maintained as a constant without change during further change in the direction of the light rays.

3. A lamp including a casing, a reflector, and a light source, with means whereby the reflector may be tilted independently of the light source to effect the light rays and change the focal relation of the light source and reflector, said means fixing the light 95 source and reflector for unit movement following a predetermined change in such focal relation, to thereby maintain a constant focal relation between the reflector and light source during further operation of such 100 means.

4. A lamp including a casing, a reflector, and a light source, means for mounting the reflector, means for tilting the reflector, the mounting of the light source permitting reflector movement to cause a diffusion of the rays from the light source during a predetermined tilting movement of the reflector, and means to cause the light source and reflector to move as a unit during further 110 tilting of the reflector, to thereby maintain the predetermined light diffusion for the final tilting movement of the reflector.

5. A lamp including a casing, a reflector, and a light source, means for tilting the reflector to affect the light rays, said light source remaining fixed during a portion of such tilting movement of the reflector to cause a predetermined diffusion of the light rays, and means whereby the light source and reflecting move as a unit following a predetermined change from their initial relation, to thereby maintain a fixed diffusion.

6. A lamp including a casing, a reflector, and a light source, means for simultaneously 125

changing the direction of the light rays and diffusion of their projection, and means for interrupting the varying diffusion at a pre-determined point without affecting the continued change in direction of such light rays.

7. A lamp including a casing, a reflector, and a light source, means for changing the direction of the light rays, and means per-

mitting a diffusion of such light rays during a portion of such change in direction less than the full change in direction movement, whereby the light is changed in direction and diffused, with the diffusion terminating at a predetermined point.

8. A lamp including a casing, a reflector, and a light source, means for tilting the reflector, a mounting for the light source, and means to permit a limited tilting of the re-

flector without affecting the light source mounting to thereby change the focal relation between the light source and reflector, and means to cause the light source mounting and reflector to move as a unit in the tilting movement of the reflector following a predetermined change in the focal relation between the light source and reflector.

9. In a means for controlling the light rays of a reflector lamp, a casing, a tiltable reflector, a bracket adjustably mounted on the casing and provided with an angularly related socket member, a lamp socket holder telescopically fitted to the socket member of the bracket and means to tilt the reflector independent of and in unison with the light source.

10. In a means for controlling the light rays of a reflector lamp, a casing, a tiltable

reflector, a bracket adjustably mounted on the casing and provided with an angularly related socket member, adapted to normally carry a light source in association with the reflector, means connected to the reflector to tilt the reflector independently and means associated with the reflector to actuate the light source to move in unison with the reflector.

11. In a means for controlling the light rays of a reflector lamp, a casing, a movable light source, a reflector hinged to the casing at the top thereof and adapted to move independently of the light source and means provided on the reflector to contact with means provided on the supporting means of the light source to actuate the light source and reflector to move together simultaneously.

12. The herein described method for controlling the rays of light reflected from a tilting reflector, consisting of first tilting a reflector independently of a light source to a pre-determined position then moving the light source and reflector in unison as and for the purpose described.

13. In a lamp for motor cars, a casing, a reflector pivoted at the top for tilting purposes, an adjustable bracket attached to the casing, a movable light source supported by the bracket, means to tilt the reflector independently of the light source to a pre-determined position and means to tilt the reflector and move the light source at said pre-determined position simultaneously.

In testimony whereof I affix my signature.

ARTHUR CHARLES WOOD.
